HEAT-TREATING STRIP

Clarence H. Verwohl, St. Clairsville, Ohio

Application June 28, 1949, Serial No. 101,755

16 Claims. (Cl. 263—2)

1

This invention relates to heat treating strip, especially metal strip, and has particular advantages in the annealing of ferrous metal strip and especially silicon steel strip.

Strip may be heat treated either in coils or continuously. Continuous heat treatment involves a large initial investment in equipment and presents other problems, particularly in the annealing of certain metals such as silicon steel which at the high temperatures to which they must be subjected tend to deposit accretions on the portions of the conveyor in the furnace or heating chamber which come in contact with the surface of the strip.

Heat treatment of strip in coils in the conventional way—with the coil axes vertical, usually with several coils stacked atop one another—has the disadvantages that the coils tend to sag and become uneven or wavy and that it is difficult to obtain uniform heat treatment throughout a coil because of the difficulty of penetration of heat into its interior. Heat treatment of strip in coils has also had the disadvantage that when a special atmosphere is used it does not readily penetrate to the interior of a tightly wound coil.

I have devised a method of and apparatus for heat treating strip overcoming the disadvantages of the prior methods. I heat treat strip in coils with the axes of the coils generally horizontal. This avoids the unevenness or waviness of the coiled metal which has heretofore been attendant upon heat treatment, especially at relatively high temperatures, of strip in coils with the coils disposed with their axes vertical. I desirably arrange strip in coil form in a heating chamber with the axis of the coil generally horizontal, apply heat to the coil and maintain the strip in coil form with the axis of the coil generally horizontal throughout the heat treatment. The positioning of the coil in the heating chamber with its axis generally horizontal exposes both edges of the strip to direct radiation of heat from the heat source or furnace walls, resulting in more rapid heating than can be accomplished by heating through the convolutions of the coil. I desirably rotate the coil about its axis during the heat treatment. The rotation may be very slow, perhaps of the order of one revolution per minute. During the heat treatment the convolutions of the coil separate somewhat at the bottom of the coil. This is due to the fact that as the temperature of the strip increases it expands or lengthens and since the outer convolutions of the coil are longer than the inner convolutions they lengthen to a greater extent. Thus during the heat treatment

2

the convolutions at the bottom of the coil are somewhat separated. As the coil rotates successive portions of the convolutions become thus separated. The result is a continuous opening up of the coil at the bottom as it rotates and a sucking in of the heated atmosphere which surrounds the coil and an expelling of that atmosphere as the successive portions of the coil move from the bottom toward the top. Thus hot gases are continuously finding their way between the convolutions of the coil at the bottom and relatively cool gases whose heat has been transferred to the coil are expelled nearer the top. In other words, the gases surrounding the coil are circulated and recirculated through it. In this way I obtain unprecedented thermal efficiency for the heat treatment of strip in coils without impairing the uniformity of the coil. The coil is maintained free from waves, being uniform from end to end.

My method and apparatus are well adapted for the heat treatment of strip in coils in special atmospheres. I desirably provide a shield device which substantially isolates the coil from the surrounding atmosphere and I may introduce a special protective or treating atmosphere within the shield device in intimate contact with the coil. The protective atmosphere may be circulated, being introduced into the space within the shield device at one point and withdrawn at another, during rotation of the mandrel on which the coil is wound. Because of the opening up of the convolutions of the coil at the bottom during the heat treatment the special atmosphere comes into intimate contact with all portions of the strip.

The shield device is proportioned to provide clearance at the periphery of the coil so that the convolutions of the coil may separate somewhat at the bottom of the coil during the heat treatment.

The strip is desirably wound on a mandrel which may have a cooling fluid passage therethrough and means may be provided for circulating cooling fluid through the passage during rotation of the mandrel while a coil of strip is being heat treated. The mandrel is preferably removably mounted for rotation in the heating chamber so that it may be bodily removed to a location remote from the heating chamber where a coil is adapted to be wound thereon and then transferred to the heating chamber and mounted for rotation therein. The heating chamber may have a removable portion adapted to be removed to provide an opening for removal and replacement of the mandrel. The heating chamber may be made in two halves, a bottom half and a top half,

and the top half may be lifted off when the coil is to be changed. A liquid seal may be provided between the bottom and top halves of the heating chamber. The cooling fluid and protective atmosphere connections may be readily disconnected to permit removal and replacement of the mandrel. Desirably the mandrel is removed to a winder where a heat treated coil is unwound from it and a new coil to be heat treated is wound onto it. The outer end of the coil may be fastened in any appropriate way, as, for example, by being welded to the convolution of the coil immediately inside it. The separation of the convolutions of the coil during the heat treatment occurs as above explained through expansion.

Material may be disposed between the convolutions of the coil as it is being wound on the mandrel to prevent adjacent convolutions from adhering to each other. Any suitable material may be employed, such, for example, as magnesium hydroxide, which may be applied by spraying.

There is no contact of any portion of the coil with any furnace conveyor mechanism other than the contact of the innermost convolution of the coil with the mandrel. Thus my heat treating method and apparatus are of especial utility in the heat treating of silicon steels and other materials which tend to deposit accretions on furnace conveyor elements as above mentioned.

Other details, objects and advantages of the invention will become apparent as the following description of a present preferred embodiment thereof and a present preferred method of practicing the same proceeds.

In the accompanying drawings I have shown a present preferred embodiment of the invention and have illustrated a present preferred method of practicing the same in which

Figure 1 is a central vertical cross-sectional view through heat treating apparatus taken on the line I—I of Figure 2; and

Figure 2 is a central vertical cross-sectional view through the heat treating apparatus shown in Figure 1 taken on the line II—II of Figure 1, Figures 1 and 2 being taken at right angles to each other.

Referring now more particularly to the drawings, there is shown a heating chamber designated generally by reference numeral 2 which comprises a stationarily mounted bottom part 3 and a complementary top part 4 which is removable from the bottom part 3 to permit the mandrel and coil presently to be described to be removed from and replaced in the heating chamber. The top part 4 is lifted by an overhead crane or other suitable lifting mechanism when the mandrel is to be removed and is replaced in position on the bottom part 3 when the mandrel is returned to its position in the heating chamber. A liquid seal 5 is provided about the heating chamber between the bottom part 3 and the top part 4 to seal the parts to the heating chamber together during operation thereof.

Means are provided for applying heat within the heating chamber 2. Any suitable heat supplying means may be employed. For purposes of illustration I have shown electric heating elements 6 mounted on the inside of the heating chamber. The heating elements are connected with a source of current and are adapted to generate the desired amount of heat within the heating chamber.

Removably mounted in the heating chamber is

75 a coil receiving mandrel designated generally by reference numeral 7. The mandrel comprises a hollow shaft 8 of suitable metal such as steel, either plain or alloy, having mounted thereon refractory sleeves 9 and steel flanges 10 carrying a steel cylinder 11, which may be of ordinary steel or a high temperature alloy steel and may conveniently be in the form of a casting, on which strip is adapted to be wound. Collars 12 are fastened to the hollow shaft 8 as by set screws to maintain the sleeves 9, flanges 10 and cylinder 11 in fixed position on the shaft. The cylinder 11 may be welded or otherwise fastened to the flanges which may in turn be welded or otherwise fastened to the hollow shaft. The space 15 between the flanges may be filled with refractory material.

20 Pedestals 13 are provided outside the heating chamber at opposite sides thereof for supporting the mandrel. A steel insert 14 is welded into each end of the hollow shaft 8, the insert itself being hollow as shown. A bearing 15 is disposed about each insert 14 and when the mandrel is in place is bolted to the corresponding pedestal 13 on which it rests. The mandrel is sealed to the heating chamber by sealing means 16 at each end. When the mandrel is in place in the heating chamber the sealing means is bolted to the heating chamber and the bearings 15 are bolted to the pedestals. When the mandrel is to be removed all of the bolts are removed so that the sealing means and the bearings are carried along with the mandrel.

25 A coil of strip is shown at 17 wound upon the mandrel. For purposes of illustration the strip may be considered to be silicon steel strip. Surrounding the coil is a shield device 18 preferably of steel and which may be of any suitable construction which isolates the coil from the surrounding atmosphere. The shield device is proportioned to provide clearance at the periphery of the coil so that the convolutions of the coil may separate somewhat at the bottom of the coil as the coil revolves during the heat treatment.

30 A protective atmosphere may be circulated within the shield device 18, being introduced through a pipe 19 and removed through a pipe 20. Cooling water for cooling the mandrel may be introduced into the hollow shaft at 21 and removed at 22.

35 Means are provided for slowly rotating the mandrel when it is in place. A sprocket 23 is fixedly mounted on the mandrel and is connected through a sprocket chain 24 with a driving sprocket 25 on the shaft 26 of a gear reducer 27 driven through a coupling 28 by an electric motor 29. The mandrel is turned very slowly at a speed of perhaps one revolution per minute.

40 I shall now describe how my method may be practiced. The bolts are removed from the sealing means 16 and the bearings 15, the sprocket chain 24 is removed from the sprocket 3 and the gas connections 19 and 20 and the water connections 21 and 22 are suitably disconnected by means which may be conventional. After disconnection of the gas connection 19 the sprocket chain 24 may be slid endwise off of the mandrel, or it may be removed from the sprocket 25 and carried along with the mandrel. The upper part 4 of the heating chamber is removed by lifting it upwardly to an out of the way position. The entire mandrel with the coil 17 thereon and carrying with it seals, bearings and sprocket is lifted up as by an overhead crane and set down on appropriate pedestals at another location where

the heat treated coil 17 is unwound from the mandrel and another coil to be heat treated is wound on the mandrel. The mandrel is then replaced in position in the heating chamber, the sprocket chain 24 is replaced, the gas and cooling water connections are reestablished, the bolts are replaced in the seals 16 and bearings 15 and the top part 4 of the heating chamber is set back in place. The electric heating elements are energized to generate heat in the heating chamber to create therein the desired temperature, generally over 1400° F., as when silicon steel strip is being annealed, cooling water is circulated through the mandrel, a desired protective or treating atmosphere is circulated within the shield device 18 and the mandrel is slowly turned. The action of the coil during the heat treatment has been explained above. Its convolutions separate somewhat at the bottom of the coil due to expansion to freely admit heat and protective atmosphere therebetween and the heated gas is alternately sucked in when the convolutions open up at the bottom and expelled when they close near the top. Thus the coil is effectively heat treated without deformation. When the coil is wound on the mandrel material to prevent the convolutions from adhering to each other may be introduced between the convolutions. For example, the strip may be sprayed with magnesium hydroxide paint as it is being wound on the mandrel.

While I have shown and described a present preferred embodiment of the invention and a present preferred method of practicing the same, it is to be distinctly understood that the invention is not limited thereto but may be otherwise variously embodied and practiced within the scope of the following claims.

I claim:

1. A method of heat-treating strip comprising arranging the strip in generally circular coil form in a heating chamber with the axis of the coil generally horizontal, applying heat to the coil and while applying heat thereto maintaining the entire strip in generally circular coil form and rotating the coil about its axis.

2. A method of heat-treating strip comprising arranging the strip in generally circular coil form in a heating chamber with the axis of the coil generally horizontal, applying a protective atmosphere to the coil, applying heat to the coil and while applying the protective atmosphere and heat maintaining the entire strip in generally circular coil form and rotating the coil about its axis.

3. A method of heat-treating strip comprising winding strip on a mandrel to form a coil, positioning the mandrel with the coil thereon in generally circular form in a heating chamber with the axis of the coil generally horizontal, applying heat to the coil and while applying heat thereto maintaining the entire strip in generally circular coil form and rotating the coil about its axis.

4. A method of heat treating strip comprising arranging the strip in generally circular coil form in a heating chamber with the axis of the coil generally horizontal, substantially isolating the coil from the surrounding atmosphere, admitting a protective atmosphere into contact with the coil, applying heat to the coil and while applying heat to the coil and while the protective atmosphere is in contact therewith maintaining the entire strip in generally circular coil form and rotating the coil about its axis.

5. A method of heat treating strip comprising arranging the strip in generally circular coil

form in a heating chamber with the axis of the coil generally horizontal, substantially isolating the coil from the surrounding atmosphere, circulating a protective atmosphere in contact with the coil, applying heat to the coil and while applying heat to the coil and circulating the protective atmosphere in contact therewith maintaining the entire strip in generally circular coil form and rotating the coil about its axis.

10 6. A method of heat treating strip comprising arranging the strip in generally circular coil form in a heating chamber with the axis of the coil generally horizontal, applying heat to the coil and maintaining the entire strip in generally circular coil form with the axis of the coil generally horizontal and with the convolutions of the coil somewhat separated at the bottom of the coil throughout the heat treatment.

15 7. A method of heat treating strip comprising arranging the strip in generally circular coil form in a heating chamber with the axis of the coil generally horizontal, applying heat to the coil, while applying heat thereto maintaining the entire strip in generally circular coil form and rotating the coil about its axis and during such treatment causing the convolutions of the coil to separate somewhat at the bottom of the coil to freely admit heat therebetween.

20 8. A method of heat treating strip comprising arranging the strip in generally circular coil form in a heating chamber with the axis of the coil generally horizontal, applying a protective atmosphere to the coil, applying heat to the coil, while applying the protective atmosphere and heat maintaining the entire strip in generally circular coil form and rotating the coil about its axis and during such treatment causing the convolutions of the coil to separate somewhat at the bottom of the coil to freely admit heat and protective atmosphere therebetween.

25 9. A method of heat treating strip comprising winding strip on a mandrel to form a coil with material between the convolutions of the coil to prevent adjacent convolutions from adhering to each other, positioning the mandrel with the coil thereon in generally circular form in a heating chamber with the axis of the coil generally horizontal, applying heat to the coil and while applying heat thereto maintaining the entire strip in generally circular coil form and rotating the coil about its axis.

30 10. A method of heat treating strip comprising winding strip on a mandrel to form a coil with material between the convolutions of the coil to prevent adjacent convolutions from adhering to each other, positioning the mandrel with the coil thereon in generally circular form in a heating chamber with the axis of the coil generally horizontal, substantially isolating the coil from the surrounding atmosphere, circulating a protective atmosphere in contact with the coil, applying heat to the coil, while applying heat to the coil and circulating the protective atmosphere in contact therewith maintaining the entire strip in generally circular coil form and rotating the coil about its axis and during such treatment causing the convolutions of the coil to separate somewhat at the bottom of the coil to freely admit heat and protective atmosphere therebetween.

35 11. Apparatus for heat treating strip comprising a heating chamber, a coil receiving mandrel adapted to receive a coil of strip to be heat treated mounted for rotation about its own axis in the heating chamber and whose axis is substantially horizontal, a shield device applicable

to the mandrel about a coil disposed thereon to substantially isolate the coil from the surrounding atmosphere and form with the mandrel a rotatable unit and means for rotating the mandrel with a coil and the shield device thereon to heat treat the strip while maintaining it in coil form and substantially isolated from the surrounding atmosphere.

12. Apparatus for heat treating strip comprising a heating chamber, a coil receiving mandrel adapted to receive a coil of strip to be heat treated removably mounted for rotation in the heating chamber and whose axis is substantially horizontal, the mandrel being adapted to be bodily removed to a location remote from the heating chamber where a coil is adapted to be wound thereon and then to be transferred to the heating chamber and mounted for rotation therein, and means for rotating the mandrel about its own axis with the coil thereon while mounted in the heating chamber to heat treat the strip while maintaining it in coil form.

13. Apparatus for heat treating strip comprising a heating chamber, a coil receiving mandrel adapted to receive a coil of strip to be heat treated mounted for rotation about its own axis in the heating chamber and whose axis is substantially horizontal, a shield device applicable to the mandrel about a coil disposed thereon to substantially isolate the coil from the surrounding atmosphere, the shield device being proportioned to provide clearance at the periphery of the coil so that the convolutions of the coil may separate somewhat at the bottom of the coil during the heat treatment, and means for rotating the mandrel with a coil and the shield device thereon to heat treat the strip while maintaining it in coil form and substantially isolated from the surrounding atmosphere.

14. Apparatus for heat treating strip comprising a heating chamber having a removable portion, a coil receiving mandrel adapted to receive a coil of strip to be heat treated removably mounted for rotation about its own axis in the heating chamber and whose axis is substantially horizontal, the mandrel being adapted to be bodily removed from the heating chamber through the opening provided by removal of the removable portion of the heating chamber to a location remote from the heating chamber where

50

a coil is adapted to be mounted thereon, and means for rotating the mandrel with a coil thereon while mounted in the heating chamber to heat treat the strip while maintaining it in coil form.

15. Apparatus for heat treating strip comprising a heating chamber, a coil receiving mandrel adapted to receive axially thereof an entire coil of strip to be heat treated mounted for rotation about its own axis in the heating chamber and whose axis is substantially horizontal, means for circulating a protective atmosphere about the coil and means for rotating the mandrel with a coil thereon to heat treat the strip while maintaining it in coil form.

16. Apparatus for heat treating strip comprising a heating chamber, a coil receiving mandrel adapted to receive a coil of strip to be heat treated mounted for rotation about its own axis in the heating chamber and whose axis is substantially horizontal, a shield device applicable to the mandrel about a coil disposed thereon to substantially isolate the coil from the surrounding atmosphere, means for circulating a protective atmosphere about the coil within the shield device and means for rotating the mandrel with a coil and the shield device thereon to heat treat the strip while maintaining it in coil form and substantially isolated from the surrounding atmosphere and in intimate contact with the protective atmosphere.
